UNITED STATES PATENT OFFICE.

LOUIS MARY, OF FEGERSHEIM, GERMANY.

POTTERY-MOLDING MACHINE.

SPECIFICATION forming part of Letters Patent No. 784,059, dated March 7, 1905.

Application filed July 29, 1904. Serial No. 218,671.

To all whom it may concern.

Be it known that I, LOUIS MARY, a subject of the Emperor of Germany, and a resident of Fegersheim, Alsace, German Empire, have invented certain new and useful Improvements in Pottery-Molding Machines, of which the following is a specification.

My invention relates to a machine for manufacturing from plastic material round articles, more especially such as possess prominences, ribs, and the like on the outer surface, the molding of which demands the employment of a split flask having positive up-and-down motion. Machines for this purpose are already well known. The present machine differs from such prior apparatus, however, inasmuch as at the period during which the flask is in its highest position and the core is molding the pot the halves or sections of the split flask are held together by rigid means. In descending the flask-sections are separated automatically by concealed springs, and the core is of such construction that its periphery only contacts with the interior of the pot at certain parts, so that the article when molded is readily released.

For the above reasons the new machine, while being of the simplest construction, is of very high capacity.

In the accompanying drawings, Figure 1 is a side elevation of the machine. Fig. 2 is a front elevation, partly in section, on line A B of Fig. 1. Fig. 3 is a sectional plan taken on the line C D of Fig. 2. Fig. 4 is an elevation of the core, and Fig. 4^a represents a horizontal section through the same.

The split flask is held in a frame or carrier *t*, which has bosses *x*, by means of which it can be slid up and down on the guide-rods *u*. This motion is imparted in well-known manner by means of the cams *c*, having grooves *n*, in which run rollers mounted on levers *h*, connected by links *a* and screw-collars *m* to the bosses *x*.

i is a cylindrical block fitting into the carrier *t* and centrally recessed to receive the two sections *g* constituting the split flask. These sections are held in the open position by means

of the springs *d*, Fig. 3, and are closed by the aid of projecting plates *z*, secured to the ends of the sections *g*, and of adjustable plates or arms *f*, pendent from the head-beam of the machine and carrying rollers *r* at their lower extremities.

k is the plate constituting the bottom of the flask, upon which the mass of clay to be molded is placed. The flask is then raised, so that the plates *z* come in contact with the rollers *r*, and as the plates *z* are provided with chamfered edges the sections *g* will gradually be pressed together and close upon the core *b*. The sections will maintain this position until on completion of molding the frame *t* descends, whereby the plates *z* are removed from contact with the rollers *r*, so that the sections *g* separate again under the action of the springs *d*, thus releasing the molded article. This arrangement has the advantage that the springs *d* are only in a state of tension during the short period of molding. In the position of rest of the machine they can expand freely, whereby their life is considerably increased. Since, however, the resistance of the springs must be overcome prior to and during molding of the pot, the carrier *t* must work with positive motion and the levers *h* must be rigidly connected with the guide-bosses *x*, so that motion of the flask must always follow that of the cam-grooves or other driving parts.

In order that the molded pot may not adhere to the core, the latter is furnished with slightly-rounded ribs *p*, Figs. 4 and 4^a, projecting to the extent of, say, one millimeter from the surface of the core-body, whereby its rotation will enlarge the pot to a small extent, sufficiently to insure the presence of a thin layer of air between core and pot.

What I claim is—

1. In a pottery-molding machine, the combination with a rotary core and vertically-reciprocating flask-carrying frame, of disconnected flask-sections held by the frame and adapted to move in horizontal lines toward and from each other, springs for moving the sections entirely away from each other, and automatically-operated means for raising the

sections and pressing them together during their ascending movement, substantially as set forth.

2. In a pottery-molding machine having a 5 rotary core and a flask-carrying frame vertically reciprocated with positive motion, a block held in the said frame, spring-controlled flask-sections located in said block, members protruding from the said flask-sections, and 10 means contacting with the said protruding

flask members and pressing the said flask-sections together on their ascent, substantially as set forth.

In testimony that I claim the foregoing as my invention I have signed my name in presence of two subscribing witnesses.

LOUIS MARY.
